(57) **CLAIM**

(21) Appl. No.: **29/132,234**

I claim the ornamental design for a function key area for a remote control, as shown.

(22) Filed: **Nov. 6, 2000**

DESCRIPTION

(30) **Foreign Application Priority Data**

FIG. 1 is a top plan view of a function key area for a remote control showing my new design; and,

May 5, 2000 (GB) 2092653

FIG. 2 is a perspective view thereof.

(51) LOC (7) Cl. **14-03**

The portion of the remote control device shown in broken lines is for illustrative purposes only and forms no part of the claimed design.

(52) U.S. Cl. **D14/218**
